UNITED STATES PATENT OFFICE

136,082

DESIGN FOR A GARMENT HANGER

Rudolph E. Schreiber, Chicago, Ill.

Application December 7, 1942, Serial No. 108,959

Term of patent 14 years

To all whom it may concern:

Be it known that I, Rudolph E. Schreiber, a citizen of the United States, residing at Chicago, in the county of Cook, and State of Illinois, have invented a new, original, and ornamental Design for a Garment Hanger, of which the following is a specification, reference being had to the accompanying drawing, forming a part thereof, in which:

Fig. 1 is a front elevational view of the garment hanger, showing my new design; and

Fig. 2 is a fragmentary end elevational view thereof.

Fig. 3 is an enlarged fragmentary inverted plan view, showing one end portion thereof.

Fig. 4 is an enlarged sectional view thereof taken on line 4—4 of Fig. 1.

I claim:

The ornamental design for a garment hanger, substantially as shown.

RUDOLPH E. SCHREIBER.
